UNITED STATES PATENT OFFICE.

EDWARD G. WATKINS AND CHARLES A. BROWN, OF GARDNER, MASSACHUSETTS,
ASSIGNORS TO HEYWOOD BROTHERS AND WAKEFIELD COMPANY, OF GARD-
NER, MASSACHUSETTS, A CORPORATION OF NEW JERSEY.

SUPPORTING-FOOT FOR ARTICLES OF FURNITURE.

1,309,868.

Specification of Letters Patent.

Patented July 15, 1919.

Application filed June 30, 1914. Serial No. 848,297.

To all whom it may concern:

Be it known that we, EDWARD G. WATKINS and CHARLES A. BROWN, both citizens of the United States, residing at Gardner, in the 5 county of Worcester and Commonwealth of Massachusetts, have invented a new and useful Improvement in Supporting-Feet for Articles of Furniture, of which the following, together with the accompanying drawings, is a specification.

The present invention relates to an improved construction of the supporting feet, for the legs of articles of furniture, such, for instance, as chairs, desks, or settees.

An object of the invention is to provide for the convenient formation of a supporting foot, from the material forming the leg of the article of furniture; a further object is to secure the exclusion of dust and dirt 20 from the corners of the leg and foot by the provision of a suitable dust cap forming part of the supporting surface of said foot.

Other and further objects will appear from the following description and the claim annexed thereto, taken in connection with the accompanying drawings, in which,

Figure 1 is a side view of an article of furniture provided with legs which embody the present invention.

Fig. 2 is a sectional view of one of the legs, on the line 2—2, Fig. 1.

Fig. 3 is a section on line 3—3, Fig. 2.

Like reference characters refer to like parts in the different figures.

Referring to the drawings, 1 indicates an article of furniture, in the present instance a combined school desk and chair, which comprises a pair of spaced apart side frames, each of which consists of a number of suitable curved lengths or strips of metal, angular in cross section, which are riveted together and braced at appropriate points. Each side frame in the present instance has a curved rear leg 2 and a vertical front leg 3, but it will be apparent that the contour of the said legs and their relation to the other parts of the structure forms no part of the present invention, which relates merely to the feet which are formed on the lower ends of said legs.

The sides of the angle bar forming each leg are pressed outwardly substantially at right angles to themselves to form integral

flat feet 4 and 5, respectively, adapted to provide extended supporting surfaces for 55 said legs. Each flat portion so formed is preferably flanged, along its edge, as shown at 6, Fig. 3, in order to secure for said leg an edge support, which is capable of being readily finished, so as to lie true on the 60 floor. The flange 6 serves also to increase the stiffness of the foot.

A dust cap 7 preferably of sheet metal, and curved substantially in the form of a segment of a sphere, so as to fit snugly within 65 the angle formed by the sides of the leg, has integral ears 8 which are riveted respectively to said sides, as shown in Figs. 2 and 3.

The dust cap 7 is disposed so that its 70 lower edge lies flush with the flange 6 of the foot, and is adapted to rest on the floor, to which each foot may be secured, if desired, by screws passing through the holes 9 thereof. Said dust cap thereby effectually 75 encloses the corner at the lower end of its leg, preventing the access of dust and dirt there- 80 to, and furthermore, increases the stiffness and strength of the leg, and enlarges the bearing surface of the foot.

It will be apparent from the foregoing 85 that angle bars of commercial shape, as well as sheet metal bars, angular in cross section, are rendered capable of use for the supporting legs of articles of furniture; and it is to 90 be noted that our invention is not limited to the particular shape of bar illustrated in the drawings, but is applicable also when bars of various angular shapes are employed for the supporting legs of articles of furniture. 95

We claim,

In an article of furniture, the combination with a leg member L-shaped in cross section and having a supporting foot at its lower end, of a triangular spherical segment 95 having its apex fitting the reentering angle of the leg member, with its sides contacting with the inner sides of the leg member and having upturned integral ears attached to the sides of the leg member.

Dated this twenty fifth day of June, 1914.

EDWARD G. WATKINS.
CHARLES A. BROWN.
